DESIGN FOR A BLANKET CLASP

Enoch B. Jorgensen, Los Angeles, Calif.

Application August 30, 1939, Serial No. 86,967

Term of patent 3½ years

To all whom it may concern:

Be it known that I, Enoch B. Jorgensen, a citizen of the United States, residing at Los Angeles, in the county of Los Angeles and State of California, have invented a new, original, and ornamental Design for a Blanket Clasp, of which the following is a specification, reference being had to the accompanying drawing forming a part thereof.

Fig. 1 is a perspective view of a blanket clasp showing my new design;

Fig. 2 is an end view of the same.

Fig. 3 is a side view of the same.

I claim:

The ornamental design for a blanket clasp, as shown.

ENOCH B. JORGENSEN.
